UNITED STATES PATENT OFFICE.

JOSEPH A. BRYAN, OF PRESCOTT, ARKANSAS.

WINDOW-SCREEN.

SPECIFICATION forming part of Letters Patent No. 357,267, dated February 8, 1887.

Application filed May 14, 1886. Serial No. 202,170. (No model.)

To all whom it may concern:

Be it known that I, JOSEPH A. BRYAN, a citizen of the United States, residing at Prescott, in the county of Nevada and State of Arkansas, have invented certain new and useful Improvements in Window-Screens; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention has relation to window-screens; and it consists in the novel construction and arrangement of its parts in connection with the attachments to the window frame and sash.

In the accompanying drawings, Figure 2 is 20 a front elevation of a window, showing my screen and attachments; Fig. 1, a vertical sectional view of Fig. 2 cut through on the line *xx*.

25 My screen consists of the upper end piece, 1, lower end piece, 2, side pieces, 3, and center piece, 4. In the open space between the pieces are iron bars 5, or heavy woven wire. Over this may be again placed, if desired, woven wire fine enough to keep out bugs, 30 candle-flies, mosquitoes, and the like. The said screen C may be fitted to any window without interfering with the arrangements of the sash already in the same.

The inner face of my screen works against 35 the "stay-strip" or inner strip, *a*, of the window-frame A, and is kept in place by an additional inner strip or stay-strip, *b*, between which strips it slides up and down. On the inner face of the upper and lower cross-pieces, 40 6 and 7, of the inner sash, B, are secured plates 8, having the perforation 9, which plates may or may not be countersunk. On the inner face of the jambs of the window-frame A, and on a line with the edges of the screen C, and at 45 the points indicated by the dotted lines 10 11, are countersunk and secured plates *c d*, similar to plates 8, having similar perforations. The objects of these perforations are herein-after shown.

50 On the under face of the top piece of the window-frame A is secured a loose pulley, D. On the upper edge of the cross-piece 1 of the

screen C are secured two loose pulleys, *e e*, on the staple 12. On the same edge of said cross-piece and at either end are secured spring-bolts 13, so situated that their locking ends are forced into the perforations of the plates *c* by their spiral springs. To the open ends of these spring-bolts are attached cords 14, which are passed under the loose pulleys *e e*, and then over the loose pulley D, and united at their loose ends by the tassel 15. A spring-bolt, 16, is passed through the lower piece, 2, of the screen, so situated and secured that when the sash B is down and the screen C is 65 also down, the locking end of the said bolt is forced by its spiral spring into the perforation 9 of the lower plate, 8, and when the said sash is down and the screw is up the locking end of said bolt is forced into the perforation of 70 the upper plate.

75 My screen is operated as follows: With one hand I take hold of the knob of the spring-bolt 16 and withdraw it from the perforation 9 in the lower plate, 8. At the same time I pull on the tassel 15. This pulls the cords 14 and withdraws the spring-bolts 13 from the perforations 9 in the lower plate, *c*. Then I push the screen up by means of the spring-bolt 16, and by slightly pulling on the tassel 15, until 80 the spring-bolt 13 comes opposite the upper plates, *d*, when the said bolts are allowed to slip into the perforations in said plates, and at the same time the spring-bolt 16 enters the perforation in the upper plate of the sash B, 85 and the screen is securely locked. The screen is let down by substantially the same operation.

The said screen may be used without the bolt 16, for the spring-bolts 13 lock it securely; 90 but I prefer to use the additional bolt for greater safety.

I am aware of the patent to Isard *et al.*, No. 272,884, wherein they use cords passing over pulleys to operate spring-bolts to screens, and 95 of the patent to Mitchell, No. 329,758, wherein he uses cords passing over pulleys to operate dogs to curtain-fixtures, and I disclaim the construction contained in either of these inventions; but

100 What I do claim as new, and desire to secure by Letters Patent, is—

1. The combination, with the window-frame A, of the screen C, additional stay-strip, *b*,

perforated plates *c d*, secured to the inner face of the jambs of said window-frame, loose pulley *D*, secured to the lower face of the upper lintel of said frame, spring-bolts 13, secured 5 to the upper edge of said screen and locking in said plates, loose pulleys *e e*, secured on the upper edge of said screen, and cords 14, having one end attached to the said spring-bolts, then passing under said loose pulleys *e e*, then over pulley *D*, substantially as shown and described.

2. The combination, with the window-frame A and sash B, of perforated plates 8, secured to the upper and lower pieces of said sash, the 15 screen C, additional stay-strip, *b*, perforated plates *c d*, secured to the inner face of the jambs of said frame, loose pulley *D*, secured

to the lower face of the upper lintel of said frame, spring-bolts 13, secured to the upper edge of said screen and locking in said plates, 20 loose pulleys *e e*, secured on the same edge of said screen, cords 14, having one end attached to each of said spring-bolts, then passing under said loose pulleys *e e*, then over pulley *D*, and spring-bolt 16, secured in the lower piece, 25 2, of said screen and locking in plates 8, substantially as shown and described.

In testimony whereof I affix my signature in presence of two witnesses.

JOSEPH A. BRYAN.
